UNITED STATES PATENT OFFICE.

THEODORE ROGATCHOFF, OF BALTIMORE, MARYLAND.

METHOD OF SHRINKING BULL-RINGS ON PISTONS.

1,326,692.

Specification of Letters Patent.

Patented Dec. 30, 1919.

Application filed December 9, 1918. Serial No. 265,952.

To all whom it may concern:

Be it known that I, THEODORE ROGATCHOFF, a citizen of the Republic of Russia, residing at Baltimore, in the State of Maryland, have 5 invented certain new and useful Improvements in Methods of Shrinking Bull-Rings on Pistons, of which the following is a specification, reference being had therein to the accompanying drawing.

10 This invention relates to new and useful improvements in a method of shrinking bull rings upon the circumferences of pistons, and comprises means whereby old and worn pistons may be reconstructed and their usefulness appreciably prolonged at a minimum of cost.

15 My invention is illustrated in the accompanying drawings which, with the numerals of reference marked thereon, form a part 20 of this application and in which:

Figure 1 is a sectional view through a worn piston adapted to be circumferentially dressed for the reception of the bull ring, as shown in dotted lines.

25 Fig. 2 is an enlarged detail sectional view of a portion of the piston as it would appear after being trimmed to receive the bull ring.

Fig. 3 is an enlarged detail sectional view 30 through a piston, parts being broken away and showing the bull ring as applied thereto.

Fig. 4 is a sectional view on line 4—4 of Fig. 3.

Fig. 5 is a sectional view vertically through a modified form of piston, showing 35 auxiliary means for holding the bull ring in place, and

Fig. 6 is a sectional view of a portion of the piston and bull ring positioned as the parts would appear before the bull ring is 40 shrunken in place.

Reference now being had to the details of the drawings by numerals:

1 designates a piston of conventional type mounted upon a piston rod 2 and provided 45 with circumferential packing rings 3 seated in grooves provided for their reception and which piston is adapted to be circumferentially cut away along angular dotted lines designated by arrows in Fig. 1 of the drawings.

50 drawings, leaving a finished circumference, as indicated in Fig. 2 of the drawings, which circumference is provided along one face with a flange 4 having an inclined edge 5, and a shoulder 6 near the opposite face, each 55 provided for an essential purpose in suc-

cessfully carrying out the method which is provided for shrinking on bull rings.

The bull ring is designated in the drawings by numeral 7 and has an inclined portion 8 adapted to conform to the inclined edge 5 of said flange 4, and also a shoulder 9 adapted to be shrunken against the shoulder 6 when the bull ring is permanently fastened to the piston.

In applying the bull ring, the latter is 65 heated to a sufficient temperature to cause the same to expand slightly and when first placed about the circumference of the piston to relieve a slight space intermediate its inner periphery and the circumference of the 70 piston, and when the inclined portion 8 of the bull ring, which is the first part to come in contact with the piston and then in contact with the inclined surface 5 of the flange, which is cold, the bull ring will be given a 75 slight movement toward the shoulder 6, and as the inner periphery of the bull ring contacts with the circumference of the piston, the shoulders 6 and 9 will interlock and be shrunken together under tremendous pressure, thus securely locking the bull ring in 80 place. As an extra precaution in holding the bull ring in place, registering holes, designated respectively by numerals 10 and 11, are formed one in the periphery of the bull 85 ring, as shown in Fig. 4 of the drawings, and the other in the wall of the piston, and in which registering holes screws 12, as shown in Fig. 3 of the drawings, may be inserted, and when adjusted in place a packing ring 3 inserted in the annular recess will 90 cover the outer ends of the screws. In Figs. 5 and 6 of the drawings I have shown a slight modification of my invention in which, instead of screws, plugs 13 are 95 mounted in registering holes, one designated by numeral 14 and formed in the wall of the piston, and the other 10^x in the inner periphery of the bull ring. After the bull ring has been shrunken and the plugs inserted, a 100 piece of welding material 13^x may close the opening in the end of the hole in the wall of the piston, as shown in Fig. 5 of the drawings.

By the provision of this method of shrinking bull rings upon pistons, as shown and described, it will be noted that a secure means is afforded for holding the same in place and at the same time affording a means for utilizing worn pistons by first 110

dressing the circumference thereof and then applying the bull ring in the manner set forth. By this method the usefulness of the piston is appreciably prolonged and at a 5 minimum of expense.

What I claim to be new is:

A method of applying bull rings to pistons, consisting of expanding by heat a bull ring having inclined and shouldered 10 portions in its periphery and placing the same about a piston, having circumferential in-

clined and shouldered portions correspond-
ing to said inclined and shouldered portions
upon the bull ring, the inclined surfaces of
the two elements causing the bull ring to 15
move slightly laterally as it shrinks, there-
by forcing the shoulders tightly together.

In testimony whereof I hereunto affix my
signature in presence of a witness.

THEODORE ROGATCHOFF.
